UNITED STATES PATENT OFFICE.

KURT FISCHER, OF COLOGNE-BRAUNSFIELD, GERMANY, ASSIGNOR TO GENERAL ELECTRIC COMPANY, A CORPORATION OF NEW YORK.

COVERING PLATE OF INSULATING MATERIAL FOR TRANSFORMERS AND OTHER HIGH-TENSION APPARATUS.

Application filed December 10, 1914. Serial No. 876,583.

To all whom it may concern:

Be it known that I, KURT FISCHER, subject of the King of Prussia, German Emperor, residing at Cologne-Braunsfeld, Germany, have invented certain new and useful Improvements in Covering Plates of Insulating Material for Transformers and Other High-Tension Apparatus, of which the following is a specification, reference being had 10 therein to the accompanying drawing.

This invention relates to improvements in covers of insulating material for casings of transformers and other high-tension apparatus.

15 A transformer or other high tension apparatus is often immersed in insulating oil within a casing having a cover through which pass the high tension conductors from the apparatus. When a metal cover is used, 20 it must be spaced a considerable distance above the top of the high tension apparatus to provide proper insulation and the high tension conductors from the apparatus must be heavily insulated where they pass through 25 the cover. Such casings have been heretofore provided with covers made of insulating material instead of metal, thus permitting a smaller spacing between the cover and the apparatus and the elimination or reduction 30 of the insulation on the high tension conductors passing through the cover. This arrangement, however, results in concentrations 35 of the electrostatic field where the high tension conductors pass through the cover and also along the upper edge of the metal wall of the casing where it meets the cover.

40 A primary object of this invention is to obviate this difficulty, and according to the invention I provide an insulating cover in which is embedded a plate-shaped condenser of predetermined capacity.

To this and other ends, the invention consists in the construction, arrangement and combination of parts described hereinafter and pointed out in the claims.

45 Several illustrative embodiments of the invention are diagrammatically represented by way of example in the accompanying drawing, wherein:—

Fig. 1 is a section of a transformer cover made according to my invention, and

Fig. 2 is a like view of a modified form; Figs. 3 and 4 are like views, respectively,

of my improved device as applied to a building structure. 55

Fig. 5 is a view of a plate-shaped leading-out device having several ducts, and

Fig. 6 is a like view of the same, having a weather-proof coating or casing. 60

Referring to Fig. 1 of the drawing, the metallic layers *a* and *b* of the condenser are located within the cover *f* which is made of insulating material, the latter being mounted upon a container *c*. These layers comprise two metallic rings, one of which, *a*, is arranged adjacent the leading-out duct *h*, whilst the other, *b*, is arranged in spaced relation with the ring *a* and adjacent the outer edge of the cover *f* and electrically connected with the container *c* as at *j* and *j'* in Fig. 2. The two layers are of a suitable size and spaced a suitable distance apart so that the voltage strain is distributed over the cover *f* and may be dealt with without 75 fear of rupture.

The cover may be made by placing sheets of insulation one on another, inserting metallic layers in correct position between said insulating material and then compressing the same. Another process of making the device consists in first winding the insulating material on a round or oval core and then pressing it. In this case the metallic layers will be wound with the insulating 85 material.

A special advantage of this kind of leading-out duct is that the available space is utilized considerably better than when cylindrical leading-out ducts projecting to either side of the cover are provided. Leading-out ducts which project a considerable distance are very inconvenient, particularly when transformers filled with oil have to be transported. Even when a cylindrical leading-out duct *g* is used in addition, as represented in Fig. 2, the height is to be, in any case, relatively only small. In this case the inner layer *a* of the cover *f* is metallically connected with a corresponding outer layer 100 *g'* of the leading-out duct *g*.

Such a cover plate can be advantageously used for leading high-tension electric currents into houses.

High tension electric currents have generally been led into houses heretofore by leading the high-voltage conductors to an insulator mounted on a support. The con- 105

ductors then pass through a suitable hole in the wall, into which a porcelain tube may be inserted. Such porcelain tubes, however, are unable to stand any material mechanical 5 stresses.

Another object of my invention is to provide a plate-shaped leading-out device for closing the wall duct.

The plate-shaped device according to my 10 invention is principally composed of insulation and is made in the form of a plate condenser. It may be used either alone or in combination with a cylindrical insulator for leading in the high-tension conductors.

15 Referring to Figs. 3 and 4, such a plate *m* includes insulation in which is embedded the metallic layers *n* and *o*, *o*. The plate is mounted at *p*, *p* and the leading-in duct is in the middle at *f'*. The distance apart of the 20 metallic layers is so selected that the voltage can be dealt with without danger of rupture.

Instead of the one duct *f'* two or more may be provided when the metallic layers are correspondingly distributed.

25 The entry of birds and insects into the transformer house is prevented by the plates, because they cover the wall duct like a window pane. When suitably constructed such a plate is able to directly take up the pull of the conductor, so that the heretofore usual insulator located in front of the duct is saved.

The cover plate whether for a transformer casing or for leading-in conductors into 30 houses or for other high-tension apparatus may also be made as a multiple duct. Such a multiple duct also has the form of a plate of insulation. One form of such a plate is shown in Fig. 5 in section. The ducts are provided at *a'*, *a'*. The condenser cover is 35 made in the form of a plate, in which metallic layers *r* and *s* are embedded. The distance between the layers is so selected that the voltage can be dealt with without danger 40 of rupture.

When a transformer has been mounted in an oil container the latter will be covered by the plate constituting a plate condenser. In 45 the case of conductors being led into a house the plate will be mounted at one end of the duct like a window pane. Instead of two ducts, more thereof may be provided if desired. The ducts may also be used in conjunction with cylindrical insulators.

The plate is preferably provided with a 55 weather-proof coating which may be made in various ways.

Fig. 6 shows one example of such a coating, it being assumed that the plate has two ducts *a'*, *a'*, as described above. The plate 60 consisting of insulation is made as a condenser comprising the metallic insertions or layers *r* and *s*. On one or both sides of the plate is mounted a sheet of glass *t* which must be intimately connected with the plate 65 in order that the air may be completely excluded. The ends and sides of the plate may also be provided with pieces of glass or with an otherwise weatherproof coating. As 70 weatherproof material mica, for example, may be used. In many cases, however, a weatherproof coating of varnish will suffice.

Having now particularly described and ascertained the nature of my said invention and in what manner the same is to be performed; I declare that what I claim is:

1. A transformer comprising a casing, a cover of insulating material carried by said casing, spaced metallic discs embedded within said cover, and means for electrically 80 connecting one of said discs to said casing.

2. A cover for transformers and the like comprising a body of insulating material, spaced metallic discs concentrically disposed within said body, and a leading-out 85 tube supported centrally of said body.

3. A cover for transformers and the like comprising a body of insulating material, spaced metallic discs concentrically disposed within said body, a leading-out tube 90 supported centrally of said body, and a condenser element within said tube and electrically connected with one of said metallic discs.

4. A cover for transformers and the like 95 comprising a body of insulating material, spaced metallic discs concentrically disposed within said body, a leading-out tube supported centrally of said body, and a metallic cylinder embedded within said tube 100 and electrically connected with one of said metallic discs.

In testimony whereof I affix my signature in the presence of two witnesses.

KURT FISCHER.
